SNOW REMOVAL MACHINE

Edward T. Stewart, St. Paul, Minn.

Application January 19, 1942, Serial No. 427,274

4 Claims. (Cl. 37—23)

This invention relates to snow removal apparatus.

It is a general object of my invention to provide snow removal apparatus which is adapted to be mounted upon a vehicle and which is so arranged that it can not only be shifted vertically relative to the vehicle but can also be moved horizontally so that snow may be picked up laterally of the path taken by the vehicle. While such a device could be mounted upon a tractor or truck it is of particular advantage on railway equipment and more specifically it has considerable advantage in railway yards where a plurality of tracks lie beside each other and considerable difficulty has been found in clearing the spaces between the tracks. This is generally done by hand and requires considerable time and labor.

Another object of the invention is to provide snow removal apparatus mounted upon a vehicle wherein the apparatus includes power operated snow pickup and disposal means with the power source mounted upon the carrying vehicle and with connections between the power source and the snow removal unit which permit power operation of the snow removal unit in various adjusted positions relative to the carrying vehicle.

A further object of the invention is to provide a vehicle supported laterally movable snow plow unit which has combined therewith means for counterbalancing the plow unit when it is laterally shifted.

These and other objects and advantages of the invention will more fully appear from the following description made in connection with the accompanying drawings, wherein like reference characters refer to the same parts throughout the views, and, in which:

Fig. 1 is a side elevation of one end of a railway car with my invention mounted thereon;

Fig. 2 is a plan view thereof;

Fig. 3 is a section taken approximately on the line 3—3 of Fig. 1;

Fig. 4 is an enlarged section taken approximately on the line 4—4 of Fig. 3;

Fig. 5 is an enlarged section taken approximately on the line 5—5 of Fig. 3;

Fig. 6 is an enlarged detail of one of the drive connections;

Fig. 7 is a front elevation; and

Fig. 8 is an enlarged horizontal section through the snow removal apparatus per se.

In Fig. 1 there is shown a railway flat car indicated generally at 9. Of course, any other suitable type of vehicle could be used. Mounted vertically on the right-hand or forward end of

the car 9 is a pair of angle irons 10 as best illustrated in Fig. 2. The angle irons 10 are braced by strengthening members 11 which extend upwardly and rearwardly from the lower portions 5 of the pair of angle irons 10 to suitable points on the car 9 as shown in Fig. 1. A yoke 12 having angled vertical side members 12a is rigidly secured to the pair of vertical angle irons 10 and said yoke has an upstanding central portion 13 10 with elongated apertures 14 formed therethrough. The vertical portions 12a of the yoke 12 are connected to an upper pair of horizontally disposed guide members 15. A lower pair 15 of similar guide members 16 is provided, it also being connected to the yoke 12. The ends of the pairs of guide members 15 and 16 are connected by posts 17a to provide a rigid structure.

Slidable between the pairs of guide members 15 and 16 are slide bars 17 and 18 respectively.

20 Extending forwardly from the slide bar 17 is a pair of horizontally disposed arms 19 which are connected to vertical posts 20 and a pair of horizontal arms 21 extends from the lower slide bar 18, said arms 21 being connected with the lower 25 ends of the vertical posts 20. The upper ends of the posts 20 are connected by a cross member 22.

The lower ends of the vertical posts 20 are connected by a cross bar 23. The ends of the cross bars 22 and 23 are shown in dotted lines in Fig. 1. 30 The slide bars 17 and 18, the pairs of forwardly extending arms 19 and 21, the vertical posts 20 and their connecting bars 22 and 23 form a frame unit which is laterally slidable relative to the yoke 12.

35 The plow unit is indicated generally at P. Extending rearwardly from the plow unit P are pairs of horizontal arms 24, 25 and 26. At either side of the machine the rear ends of the arms are connected by vertical posts 27. The right-hand 40 post 27 has a rearward extension 28 which supports a hydraulic motor 29. Extending between the vertical posts 27 are shafts 30, 31, 32 and 33.

Also extending rearwardly from the plow P are apertured lugs 34 which slidably receive the vertical members 28 which are connected to the arms 19 and 21 extending forwardly from the slide bars 17 and 18. Thus the plow unit P can be shifted vertically relative to forwardly extending arms 19 and 21 and vertical members 28, and the plow unit can be shifted laterally of said members 19, 20 and 21. Vertical movement of the plow unit and the rearwardly extending arms 24, 25 and 26 is effected by means of hydraulically operated cylinder and piston units 35 which have suitable 55 hydraulic lines 36 connected to the unit to actu-

ate the same vertically. The cylinder and piston unit rests upon a cross arm 37 which extends between the upper arms 24 extending rearwardly from the plow unit and the piston rod 38 is shown in Fig. 1 to connect with the cross member 22 which extends between the upper ends of the vertical posts 20 on the laterally shiftable frame.

Lateral movement of the plow unit P and its supporting frames is effected by means of the hydraulic motor 29 and a threaded shaft 39 as shown in Figs. 1 and 3. Shaft 39 extends between the rearward extensions 28 of the vertical members 27 which are connected at either side of the machine to the horizontal rearwardly extending members 24, 25 and 26. A lug 40 threadedly receives the screw 39 and said lug is held against lateral movement by means of guide members 41 secured to a plate 42, as best indicated in Figs. 3 and 4. The plate 42 is rigidly secured to two of the adjacent cross members 15 and 16 which form portions of the guides for the slide bars 17 and 18. When the hydraulic motor 29 is actuated the screw 39 will be rotated and due to its interconnection with the lug 40 the entire plow assembly will be shifted laterally relative to the car 9. When the plow assembly is moved vertically under the influence of the hydraulic cylinder and piston assembly 35 the lug 40 will slide vertically between the guides 40 provided therefor.

To brace the snow plow assembly I provide brace arms 43 and 44 at either side of the car 9. The forward ends of said brace bars 43 and 44 are connected respectively to the laterally movable slide bars 17 and 18. The forward ends of said braces 43 and 44 are provided with yokes 45 and 46 which are pivotally connected to rods 47 which extend to the slide bars 17 and 18 a considerable distance, as shown in Fig. 3, and said rods 47 are adapted to slide into and out of said slide bars 17 and 18. The rear ends of the braces 43 and 44 are connected to a link 48 which in turn is pivotally connected at its center to a piston rod 49 working in a hydraulic cylinder 50. There is a cylinder and piston assembly 49, 50 at each side of the car and, as indicated in Fig. 2, the cylinders 50 are connected by a line 51 and are connected to a suitable pressure control device (not shown) to permit either set of braces 43, 44 to give. Referring to Fig. 2 it will, of course, be seen that the snow plow assembly is centered relative to the car 9. If the screw 39 is actuated to shift the entire assembly to the right, as viewed in Fig. 2, the left-hand braces 43 and 44 will strike against the stationary frame with its vertical end members 17a, and as the assembly moves to the right the left-hand rods 47 at the ends of the braces 43 and 44 will have a relative sliding movement outwardly from the left-hand ends of the slide bars 17 and 18. The right-hand braces 43 and 44 will move to the right at their forward ends with the laterally movable portion of the assembly, and the hydraulic cylinder and piston assembly 49, 50 will provide the additional length required since said right-hand brace bars 43, 44 will then form a hypotenuse of a triangle. Springs 52 are connected between the braces 43 and 44 and suitable portions of the relatively stationary frame such as bolts 53 which clamp the vertical angle irons 10 to the forward portion of the car 9. These springs 52 yieldingly urge the braces 43 and 44 inwardly so that they will naturally assume the positions shown in Fig. 2 when the plow assembly is centered relative to the car 9. On the for-

ward end of the car 9 I provide a counterweight 54 which has an upstanding lug or ear 55 having a threaded aperture therethrough to receive a screw 56. The counterweight 54 lies in and is guided by a trackway 57 which allows lateral movement of the counterweight 54 upon rotation of the screw 56 by a hydraulic motor 58 which is geared to the screw 56 by a chain drive 59. The fluid motor 29 which actuates the screw 39 to shift the plow assembly laterally is provided with a fluid conduit 60 which is also connected with the fluid motor 58 which actuates the counterweight screw 56 and the two fluid motors 29 and 58 are connected in such a manner that as the plow assembly shifts to the right the counterweight 54 will shift to the left, thus to a certain extent relieving strains due to lack of balance.

The snow plow per se indicated generally at P may conveniently be a plow such as disclosed in my prior United States Patent Number 2,075,673, issued March 30, 1937. In general the plow includes a casing 61 having a plurality of screws 62 rotatably mounted therein to break up the snow and feed it toward the center portion of the casing 61. The snow is forced inwardly and rearwardly and it passes through an opening 63 to a chamber 64 housing a fan 65. The fan discharges the snow through a lateral outlet 66. In Fig. 2 the outlet is shown at the left of the machine, but snow can be discharged to the right by swinging the pivoted deflector 67 to the left so that an outlet opening would then be exposed at the right-hand side of the fan casing 64. It is, of course, necessary to reverse the rotation of the fan 65 when the pivoted deflector 67 is reversed in position.

A suitable source of power such as an internal combustion engine 68 is mounted upon the car 9. A telescopic drive connection 69, 70 connects the engine 68 to the cross shaft 31 by means of a bevel gear unit 71. The shaft 31 is connected to a lower cross shaft 33 by means of a chain drive 72 and said cross shaft 33 is connected by a chain 73 to a shaft 74 which, as best shown in Fig. 7, carries the lower of the two horizontal snow conveying screws 63. A chain 75 connects the lower horizontal screw shaft 74 to the upper horizontal screw shaft 76. The shaft 76 on its inner end carries a pinion gear 77 which meshes with a ring gear 78 which is mounted upon a shaft 79 suitably journaled in the central nose or casing 80. It will be seen in Fig. 8 that the ring gear 78 has a pair of toothed circular faces. The pinion 77 engages one set of teeth and another pinion 81 engages the same teeth. Pinion 81 is on a shaft 82 which forms the other half of the shaft for the upper horizontal snow conveying screw 62. Without going into detail it can be seen that the other screw shafts are suitably geared to the second set of teeth on the other face of the ring gear 78.

A second engine 83 is mounted on the car 9 beside the above described engine 68 and it is connected by telescopic drive shaft 84, 85 to a bevel gear assembly 86 to drive the upper cross shaft 30. This shaft is connected by a chain drive 87 to the cross shaft 32 and, as best shown in Fig. 8, the cross shaft 32 carries a bevel gear 88 which meshes with the bevel gear 89 on the shaft 90 which carries the snow blower or fan 65.

In Fig. 6 there is shown a detail of the connection between the telescoping drive shaft portion 85 and the upper cross shaft 30 through the bevel gear unit 86. This gear connection is held

in position by a yoke 91 which, as shown, pivotally receives the forward end of the drive shaft 85 and which has arms which rotatably connect with the upper cross shaft 30. The cross shaft 30 is arranged for sliding movement through the bearing tube 92. The arrangement on the drive shaft 70 which is connected to the engine 68 is essentially the same as in Fig. 6.

Due to the fact that the drive shafts 70 and 85 move vertically with the vertically movable plow assembly the upper extension 13 on the yoke 13 is provided with vertical slots 13 so that the shafts 70 and 85 are braced to some extent by said upward extension 13 but are permitted to move vertically relative thereto.

From the foregoing description it will be seen that I have provided snow removal apparatus which can be mounted on a railway flat car in such a way that not only its vertical position can be adjusted but it may also be shifted laterally relative to the car upon which it is mounted. The device is provided with a counterbalance to offset the laterally shifted weight of the plow unit and the drive connections for the snow conveying and blowing apparatus are so arranged that they will function in any of the adjusted positions to which the plow is shifted. It is a device which is effective in removing snow in railway yards where hitherto it has been necessary to clean away the snow from between the tracks by hand. While it is primarily designed for railway use it should, of course, be understood that it can be effectively used on trucks or tractors for cleaning the shoulders of highways while keeping the carrying vehicle on the pavement.

I have shown my invention in connection with a rotary snow plow such as disclosed in the above identified patent issued to me but, of course, it is not necessary that this specific type of rotary plow be used in conjunction with the plow shifting mechanism disclosed herein.

It further will be understood that various changes may be made in the form, details, ar-

rangement and proportions of the various parts without departing from the scope of my invention.

What is claimed is:

5. 1. Snow removing apparatus including, a relatively stationary support, a relatively movable frame, a snow plow unit on said relatively movable frame, a connection between said relatively stationary support and said relatively movable frame permitting said relatively movable frame and plow unit to move laterally relative to said stationary support, and counterbalancing means on said support movable laterally and oppositely to said movable frame and plow unit when said frame and plow unit are moved to off-center positions.
- 10 2. The structure in claim 1 and said counterbalancing means and said movable frame and plow unit being synchronously power actuated.
- 15 3. Snow removing apparatus including, an ambulant support, a plow unit connected to said support for lateral movement relative thereto, brace members extending from said ambulant support to said laterally movable plow unit and means for compensating for the differences in distance between the points of connection of said brace members on said ambulant support and said plow unit in various laterally disposed positions of said plow unit.
- 20 4. Snow removing apparatus including, a relatively stationary support, a relatively movable frame, a snow plow unit on said relatively movable frame, a connection between said relatively stationary support and said relatively movable frame permitting said relatively movable frame and plow unit to move laterally in a straight line relative to said stationary support, and counterbalancing means on said support movable laterally and oppositely to said movable frame and plow unit when said frame and plow unit are moved to off-center positions.
